US0D1066707S

(12) **United States Design Patent** (10) Patent No.: **US D1,066,707 S**
(45) Date of Patent: ** Mar. 11, 2025

(54) **PHOTOTHERAPY EQUIPMENT**

(71) Applicant: "SCI Health", UAB, Vilnius (LT)

(72) Inventor: **Romualdas Rudys**, Miežiškiu mstl. (LT)

(**) Term: **15 Years**

(21) Appl. No.: **35/519,227**

(22) Filed: **Nov. 8, 2023**

(80) **Hague Agreement Data**

Int. Filing Date: **Nov. 8, 2023**

Int. Reg. No.: **DM/233352**

Int. Reg. Date: **Nov. 8, 2023**

Int. Reg. Pub. Date: **Dec. 1, 2023**

(51) **LOC (15) Cl. 24-01**

(52) **U.S. Cl.**

USPC **D24/209**

(57) **CLAIM**

The ornamental design for phototherapy equipment as shown and described.

DESCRIPTION

1. Phototherapy equipment

FIG. 1.1: is a perspective view of the design

FIG. 1.2: is a perspective view of the unfolded design

FIG. 1.3: is a rear view of the design

FIG. 1.4: is a left side view of the design

FIG. 1.5: is a right side view of the design

FIG. 1.6: is a top view of the design

FIG. 1.7: is a bottom view of the design

FIG. 1.8: is a rear view of the design

The portions of the article shown inside of the dashed broken line of FIG. 1.7 form no part of the claimed design.

1 Claim, 8 Drawing Sheets
